UNITED STATES PATENT OFFICE

99,752

DESIGN FOR A COMBINATION JUICE EXTRACTOR AND FOOD MIXER

Francis John Osuch, Detroit, Mich., assignor to Robot Hand Corporation, Detroit, Mich., a corporation of Delaware

Application March 25, 1936, Serial No. 61,773

Term of patent 14 years

To all whom it may concern:

Be it known that I, Francis John Osuch, a citizen of the United States, residing at Detroit, in the county of Wayne and State of Michigan, have invented a new, original, and ornamental Design for a Combination Juice Extractor and Food Mixer, of which the following is a specification, reference being had to the accompanying drawing forming part thereof.

The figure is a perspective view of a combination juice extractor and food mixer showing my new design.

I claim:

The ornamental design for a combination juice extractor and food mixer, as shown.

FRANCIS JOHN OSUCH.
